UNITED STATES PATENT OFFICE.

CHARLES J. AHRENFELDT, OF NEW YORK, N. Y.

DESIGN FOR A CUP.

SPECIFICATION forming part of Design No. 30,521, dated April 11, 1899.

Application filed January 11, 1899. Serial No. 701,888. Term of patent 3¹ years.

To all whom it may concern:

Be it known that I, CHARLES J. AHRENFELDT, a citizen of the United States, residing in the city of New York, county of New York, and State of New York, have invented and produced a new and original Design for a Cup, of which the following is a specification, reference being had to the accompanying drawings, forming a part thereof, like letters referring to like parts in each figure of the same.

In the drawings, Figure 1 is a side view of a cup embodying my design. Fig. 2 is a bottom view of the same. Fig. 3 is a horizontal section taken on the line 3-3 of Fig. 1 and looking in the direction indicated by the arrow.

The body of the cup is bell-shaped, with an upper edge or brim having a plain circular periphery A. A short distance below this edge are a series of vertical indentations or furrows B, running down to the base C. There are four indentations in each set and four sets around the cup, thus giving the surface of the cup a wave-like appearance in section, as shown in Fig. 3, with three small waves and one large wave alternated.

The base C of the cup is quadrisectioned by

four indentations D in its lower edge, and on either side of the cup, just above this base, is an ornamentation, which consists of a central panel E, of three vertical divisions bordered on either side by a C-shaped arabesque F, with a stem bearing leafed and floral ornaments G extending from the upper part of the C. An ornament consisting of a central panel with a C-shaped arabesque on either side H is located on the remaining two sides just above the base.

The handle I projects from the side of the cup at the bulged portion thereof and is made to resemble a number of lily leaves bound together and secured at the upper end to a curled knob J, projecting from the upper part of the cup.

What I claim is—

The design for a cup herein shown and described.

Signed at the city of New York this 4th day of January, 1899.

CHARLES J. AHRENFELDT.
